US00D783576S

(12) **United States Design Patent** (10) **Patent No.:** **US D783,576 S**
(45) **Date of Patent:** **** Apr. 11, 2017**

(54) **EARBUD CONNECTOR PLATE**

(71) Applicant: **Oculus VR, LLC**, Menlo Park, CA (US)

(72) Inventors: **Peter Wesley Bristol**, Seattle, WA (US); **Quintin Morris**, Issaquah, WA (US); **James Stocker Webb**, Seattle, WA (US); **Mark Shintaro Ando**, Seattle, WA (US); **David Tao**, Santa Clara, CA (US); **Dan Faulkner**, Menlo Park, CA (US)

(73) Assignee: **Oculus VR, LLC**, Menlo Park, CA (US)

(**) Term: **15 Years**

(21) Appl. No.: **29/550,170**

(22) Filed: **Dec. 30, 2015**

(51) LOC (10) Cl. **14-01**

(52) U.S. Cl.

CLAIM

The ornamental design for a earbud connector plate, as shown and described.

DESCRIPTION

FIG. 1 is a front isometric view of a left earbud connector plate showing our new design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof.

FIG. 8 is a front isometric view of a right earbud connector plate showing our new design.

FIG. 9 is a front elevation view thereof.

FIG. 10 is a rear elevation view thereof.

FIG. 11 is a left side elevation view thereof.

FIG. 12 is a right side elevation view thereof.

FIG. 13 is a top plan view thereof; and,

FIG. 14 is a bottom plan view thereof.

Any broken lines in the Figures are for illustrative purposes only and form no part of the claimed design.

1 Claim, 10 Drawing Sheets
